Primary Examiner — T Chase Nelson(74) Attorney, Agent, or Firm — Banner & Witcoff, Ltd.CLAIM

The ornamental design for a shoe as shown and described.

DESCRIPTIONFIG. 1 is a front perspective view of a shoe showing my new design;
FIG. 2 is a side view thereof;
FIG. 3 is a rear perspective view thereof;
FIG. 4 is a bottom view thereof;FIG. 5 is an opposite side front perspective view thereof;
FIG. 6 is an opposite side view thereof;FIG. 7 is an opposite side rear perspective view thereof; and,
FIG. 8 is a bottom side rear perspective view thereof.

The even-length broken lines represent stitching that forms no part of the claimed design. The uneven-length broken lines depicting the remainder of the shoe form no part of the claimed design.
